HIGH POWER TRANSMIT-RECEIVE BOX

Louis D. Smullin, Arlington, Mass., assignor, by
mesne assignments, to the United States of
America as represented by the Secretary of the
Navy

Application August 2, 1945, Serial No. 608,593

2 Claims. (Cl. 333—13)

1

This invention relates to transmit-receive boxes and more particularly to an improved box of the class indicated having novel tuning means inserted therein and constructed to provide a minimum of leakage power through the box.

Transmit-receive boxes, hereinafter referred to as TR boxes, are commonly used in connection with transmit-receive circuits having a common antenna to electrically cut off the receiver from the circuit at all times during which the transmitter is in operation. TR boxes of common construction have not proven entirely satisfactory due to leakage of power through the box during intervals in which the transmitter is operative, thereby shortening the life of the crystal detector commonly used in the receiver circuit.

An object of this invention is to provide an improved transmit-receive box of such construction as to afford a minimum of power leakage through the box.

Another object of this invention is to provide a TR box having adjustable means for increasing the direct coupling attenuation through the resonant cavity of the box.

A particular object of this invention is to provide a tunable TR box having means for adjustably tuning the resonant cavity of the box.

A more particular object of this invention is to provide a TR box having attenuation plugs electrically connected to two opposite walls of the resonant cavity irrespective of the depth to which the plugs may be inserted in said cavity.

Further objects and advantages of this invention as well as its construction, arrangement, and operation, will be apparent from the following description and claims in conjunction with the accompanying drawings, in which:

Fig. 1 is a schematic diagram of a section of a wave guide having a standard TR box connected directly to one side of the guide.

Fig. 2 is a schematic diagram of one form of the present invention including tuning plugs of a construction and operation hereinafter to be described.

Fig. 3 is a front elevation taken along the lines III—III of Fig. 2.

Fig. 4 is a schematic diagram of a second embodiment of the invention shown in Fig. 2 having a plurality of uniformly disposed tuning plugs adjustably mounted on the wall of the TR box.

Referring to Fig. 1, there is shown a schematic diagram of a section of a wave guide 20 with a standard TR box having a wall 21 enclosing a

2

resonant cavity 22 connected directly to one side of wave guide 20 by means of an opening or window 23 in the side of the wave guide. The output coupling of the TR box is by means of a probe or loop 24, coupling the magnetic field. Magnetic field distribution lines 25 are shown for the condition in which the TR box is fired, pointing out diagrammatically the manner in which the distribution of the magnetic field falls off exponentially from window 23 to output probe 24. One of a pair of cones commonly used in TR tubes is shown and indicated by numeral 26.

Fig. 2 illustrates one form of the present invention in which all parts are common to those of Fig. 1, but including metallic plugs 27 and 28 of electrically conductive material for shorting out the magnetic field as it progresses across the box. As shown, plugs 27 and 28 are adjustably mounted through suitable openings in wall 21 so that they may be moved into and out of resonant cavity 22. A glass TR tube and one of the cones forming the spark gap of said tube are indicated at 29 and 26 respectively.

Fig. 3 is a front elevation taken along the lines III—III of Fig. 2 further illustrating the invention as shown in Fig. 2. A pair of walls 30 and 31 are shown which, together with wall 21, complete the enclosure of resonant cavity 22. TR tube 29 and cones 26 are more clearly illustrated in this view. Tuning plugs 27 and 28 are shown having a diameter equal to the thickness of cavity 22, this distance being equal in value to the distance between walls 30 and 31, which is the height of wall 21. The inner surfaces of walls 30 and 31 are provided with threaded portions so that plugs 27 and 28 may be moved into and out of cavity 22, while retaining electrical contact with walls 30 and 31 at all times. In this manner, plugs 27 and 28 provide a complete block to the passage of electromagnetic radiation for the depth of their insertion in cavity 22. In addition to completely physically blocking off cavity 22 in so far as they are inserted into the cavity, plugs 27 and 28, at the same time, electrically short out the magnetic waves to walls 30 and 31. It has further been discovered that if D be the diameter of a TR box as shown in Fig. 1 tuned for resonance at a certain frequency, and if d be the distance between opposite faces of attenuation plugs as shown in Fig. 2 in which the plugs are adjusted to cause the box to become resonant at the same frequency, the value of d is much smaller than the value of D of a standard TR box not supplied with attenuation plugs as contemplated by our invention. It will

readily be understood that the diameter of a TR box equipped with attenuation plugs may be much greater than one not supplied with such plugs when both boxes are tuned to the same resonant frequency. Therefore the distance between the input source and output probe of a TR box equipped with attenuation plugs as described may be much larger than a box not so equipped. Since the magnetic field intensity distribution between the input source and output probe falls off exponentially with the distance therebetween, the leakage of power by direct coupling may be reduced to a minimum without loss of resonant tuning of the box. It is the combination of increased distance across the box and shorting-out effect of the attenuation plugs that assures a minimum of power leakage from input source to output probe.

Fig. 4 is similar in all respects to Fig. 3 with the exception of the addition of a second pair of attenuation plugs and the orientation of the plugs with respect to the input window and output probe of the tube. As shown, four adjustable attenuation plugs 32, 33, 34 and 35 are employed to short out the magnetic field and to provide resonant tuning of the box. In this embodiment of the invention, the effective diameter of the TR box is the distance between the inside faces of the opposite plugs. It will readily be understood from the foregoing discussion in connection with Figs. 2 and 3 that the coupling space between window 23 and output probe 24 may be substantially increased over that of a standard TR box, while oppositely disposed attenuation plugs 32, 33, 34, and 35, respectively, make it possible for the resonance of the box to be tuned in spite of this increase in coupling space. Likewise, it will readily be understood that since the diameter of these attenuation plugs is equal to the thickness of the TR box, and since these plugs are electrically connected to the walls of the box at all times, the combination blocking and shorting out effect of the plugs together with the increased coupling space made possible through use of the plugs provides an improved TR box in which the power leakage from input source to output probe may be reduced to a minimum.

While two embodiments of the invention have been disclosed and described, it is to be understood that various modifications and changes may be made in this invention without departing from the spirit and scope thereof as set forth in the appended claims.

What is claimed is:

1. A tunable transmit-receive box comprising two parallel plane electrically conductive walls

joined to a cylindrical electrically conductive wall, said walls enclosing a resonant cavity, means at said cylindrical wall for introducing electromagnetic energy into said cavity, additional means at said cylindrical wall diametrically opposite said introducing means for extracting said electromagnetic energy, and a pair of electrically conductive plugs adjustably mounted in said cylindrical wall and extending into said cavity, one member of said pair being disposed diametrically opposite the other member of said pair, a line extending diametrically through said pair of plugs being transverse to a line extending diametrically through said introducing and extracting means, each of said plugs being equal in diameter to the spacing between said parallel walls and being in electrical contact with said parallel walls irrespective of the depth to which it is inserted into said cavity.

2. A tunable transmit-receive box comprising two parallel plane, electrically conductive walls joined to a cylindrical electrically conductive wall, said walls enclosing a resonant cavity, means for introducing electromagnetic energy through said cylindrical wall into said cavity, means for extracting said energy from said cavity through said cylindrical wall, said introducing means and said extracting means being diametrically opposite one another, and a plurality of pairs of electrically conductive plugs adjustably mounted in said cylindrical wall and extending into said cavity, each member of each pair of said plugs being disposed diametrically opposite the other member of the same pair, said plugs being disposed symmetrically with respect to a line extending through said introducing means and said extracting means, each of said plugs also being equal in diameter to the spacing between said parallel walls and being in electrical contact with said parallel walls irrespective of the depth to which it is inserted into said cavity.

LOUIS D. SMULLIN.
